UNITED STATES PATENT OFFICE.

ERNEST WILLIAMS, OF NEW YORK, N. Y.

SOOT AND SCALE EJECTOR.

1,189,328.

Specification of Letters Patent.

Patented July 4, 1916.

Application filed May 27, 1913. Serial No. 770,273.

To all whom it may concern:

Be it known that I, ERNEST WILLIAMS, a citizen of the United States, and resident of New York city, in the county of New York and State of New York, have invented certain new and useful Soot and Scale Ejectors, of which the following is a specification.

My invention relates to the improvement in the apparatus for the removal of soot and scale accumulating in the soot settling or combustion chamber of steam generating boilers.

The object of my invention is to discharge the soot and scale directly into the ash pit of the boiler, wetting it down during the process of transmission, so that it will be in a state to permit its removal with the ashes, thus eliminating the dust stirred up by the removal by hand and saving a large amount of labor and haulage in accomplishing the same object. I obtain these results by the apparatus illustrated in the accompanying drawing in which:—

Figure 1, is a vertical section through a steam generating boiler showing the relative position of the ejector. Fig. 2, is a vertical section through the soot ejector.

Similar letters refer to similar parts in the same views.

“A” is the chamber where the soot and scale accumulate.

“B” is the ash pit into which the ashes are dumped from the grate and fire box above and into which the soot and scale are discharged.

“C” is a funnel shaped collector for leading the soot and scale into the ejector.

“D” is a sliding damper for the regulation of material entering the ejector.

“E” is the suction chamber of the ejector.

“F” is the jetting device carrying the suction producing element.

“G” is the discharge chamber.

“H” is the spray chamber supplying the spray openings.

“I” is one of the various spray openings emanating from the spray chamber for the wetting down of material before discharging into ash pit “B.”

“J” is the pipe for transmission of the spraying element to spray chamber.

“K” is the pedestal for the support of ejector below “D.”

“L” is a handhole cap for the removal of “F” and the clearing out of “E” and “G.”

The soot which accumulates in the chamber “A” is in a powdery state and very light in weight and its removal by hand is laborious and detrimental to the general health of persons removing same, due to its being inhaled and drifting into the exposed natural cavities of the body.

The action of the ejector is as follows: The soot and other refuse material accumulates in the chamber “A,” also filling the collector “C.” The valve controlling the suction producing element flowing in the pipe “F” is opened and a partial vacuum produced in the suction chamber “E.” The valve controlling the admission of the spraying element to the spray chamber “H” is now opened. The damper “D” is opened and the material from chute “C” and chamber “A” admitted to the suction chamber “E” from which it is drawn into the discharge chamber “G” being sprayed in its transmission and delivered in a plastic form into the ash pit “B.”

I claim:

1. In a soot and refuse removal unit an ejector or conveyer tube having a single discharge orifice, together with an inlet hopper at the suction end, said inlet hopper being directly connected through a damper to the conveyer tube, a single steam or compressed air jetting device located between the damper and the discharge orifice, said jetting device having a single outlet orifice and being rigidly connected to a removable plate, which plate is fastened to the exterior of the ejector tube, a plurality of water spray nozzles set adjacent to the discharge orifice of the conveyer tube and extending from the interior of the conveyer tube to a chamber of annular form, encircling a portion of the exterior of the conveyer tube; together with the controlling means substantially as shown, for the purposes as specified.

100

2. In a soot and refuse removal unit a conveyer tube having a single jetting device, which jetting device is removable through an opening in the side of the conveyer tube, 5 said jetting device being rigidly connected to a removable plate, said plate being attached to exterior of the conveyer tube, which plate seals opening in the conveyer tube, said plate having lug for pipe connection to same; together with the controlling

means substantially as shown, for the purposes as specified.

Signed at New York city in the county of New York and State of New York this 24th day of May A. D. 1913.

ERNEST WILLIAMS.
